I claim the ornamental design for a communion box, as shown and described.

DESCRIPTION

FIG. 1 is a top plan view of a communion box, showing my new design in a flat configuration with a plurality of communion wine and wafer cups and a cup tray omitted for clarity of illustration, the bottom plan view being a mirror image thereof;

FIG. 2 is a perspective view thereof, the box illustrated in an assembled and open configuration, one of the plurality of communion wine and wafer cups shown exploded away therefrom;

FIG. 3 is a rear elevational view of FIG. 2;

FIG. 4 is an unexploded front elevational view of FIG. 2;

FIG. 5 is a right-side elevational view of FIG. 4, the left-side elevational view being a mirror image thereof;

FIG. 6 is a top plan view of FIG. 4;

FIG. 7 is a bottom plan view of FIG. 4;

FIG. 8 is a top perspective view thereof, the box illustrated in a closed configuration; and,

FIG. 9 is a bottom perspective view of FIG. 9.
